PROCESS OF REFINING AND TREATING
PETROLEUM HYDROCARBONS

William T. Hancock, Long Beach, Calif.

Application January 10, 1940, Serial No. 313,223

7 Claims. (Cl. 196—96)

This invention has to do with processes for the cracking and refining of petroleum hydrocarbons to produce gasoline, and has for its general object to provide an improved system that is particularly adaptable for the cracking of relatively low boiling cracking stocks to produce high yields of gasoline having abnormally high octane rating.

The invention may be further characterized as incorporating in a cracking system, a method of subjecting the cracked hydrocarbons to polymerization by contacting them with adsorptive material, and further, if desired, of subjecting relatively heavy fractions of the polymerized hydrocarbons to re-cracking, all with the object of converting a given cracking stock into maximum potential gasoline forming constituents, and reforming these constituents by polymerization into condensable gasoline fractions. By reason of the adaptability of the system to initial dissociation of the cracking stock into high percentages of potential aromatic and other non-detonating type hydrocarbons, and then the conversion by polymerization or catalytic action of the cracked products into such hydrocarbons, it is made possible to produce an exceptionally high quality gasoline.

Preferably the system is operated using, as stated, a relatively low boiling charging stock which is subjected to vaporization and cracking and the vapors introduced to a polymerizing zone wherein they are intimately contacted with a suitable catalytic or adsorptive material. Particularly where it is desired to introduce all the cracked hydrocarbon directly from the cracking zone into the polymerizing chamber, provision is made for maintaining liquid and vapor fractions of the hydrocarbons in intimate contact within the adsorptive material so as to increase its catalytic and polymerizing effectiveness, and to accomplish by washing action, the removal from the material of contaminating bodies such as carbon or heavy hydrocarbons and polymers.

Unvaporized or condensed relatively heavy fractions of the hydrocarbons subjected to polymerization, are recirculated for cracking in a second cracking zone, the cracked hydrocarbons from which are polymerized by passing them through the adsorptive material in the polymerizing zone receiving hydrocarbons from the first mentioned cracking zone, or delivered to a second similar polymerizing zone. Condensate or unvaporized oil thus recirculated for cracking may be taken from one or both polymerizing zones. The combined polymerized vapors from

both cracking zones may be subjected to treatment to produce the product gasoline by any suitable method, as by subjecting the vapors to fractionation and then final condensation.

The operation of the invention and the various features and objects mentioned in the foregoing, will be further explained and understood to better advantage from the following description of a typical system embodying the invention, illustrated diagrammatically and in flow sheet form in the accompanying drawing.

The preferred charging stock may comprise relatively low octane gasoline, kerosene distillate and in general hydrocarbons that are sufficiently low boiling not to produce excessive carbon or residue contamination of clay in the conversion zone. The charging stock is delivered from line 10 to the cracking still 11 wherein the hydrocarbons may be subjected to cracking in either liquid or vapor phase, or mixed liquid and vapor phase, at a temperature that typically may range from 800 to 1200° F. under suitable pressure of for example 50 to 400 lbs. per sq. in. Leaving the cracking still, the cracked hydrocarbon stream is discharged through line 12 into a shell or chamber 13 containing a suitable comminuted siliceous material, preferably adsorptive clay such as fuller's earth, Murock or Death Valley clays, and the like. As will be understood, the clay may also contain or have been pre-treated with any or a mixture of known substances of a reactive or catalytic nature, adapted in the case of the former to react with and thereby accomplish the removal of impurities such as acid or sulfur constituents of the hydrocarbons, and in the case of the catalysts, to catalyze the cracking reaction, or to induce more complete polymerization. Various metals, metallic oxides and metallic salts are commonly known as suitable reactive or catalytic agents. Entering chamber 13, the hydrocarbons are intimately contacted with the adsorptive material 14, the vapors rising upwardly through the material to the outlet line 15, and any unvaporized fractions flowing downward to the bottom of the chamber where they are taken off through line 16.

Where the cracked hydrocarbons are discharged from still 11 directly into a clay column, as in the typical system illustrated, it is important from both the standpoints of producing maximum catalytic or polymerizing action of the clay, and of maintaining the latter as free as possible from contamination by carbon or heavy residual bodies carried in the cracked hydrocarbon stream, that a mixture of liquid and

vapor fractions be maintained in intimate contact and agitated washing action within the clay. For this purpose I may deliver to the upper interior of the clay column a suitable light hydrocarbon reflux, or produce the necessary reflux by partial condensation of the cracked vapors, so that the vapors rising within the clay are contacted with a down-flowing stream of reflux, the two phases being intimately commingled and maintained in such a state of washing agitation as to effectively remove solid or heavy bodies from the clay to the draw off line 16.

Reflux to be introduced to the clay column may be taken, for example, from the supply line 10 and discharged directly through lines 17, 18 15 and 19 into the top of chamber 13, or the oil may be pre-heated in coil 20 to a suitable temperature that may approach the outlet vapor temperature of the clay column, before being introduced thereto. Optionally, a suitable reflux may be derived from a later stage in the system, as from the base of fractionating column 21 through line 22. Instead of introducing reflux from an extraneous source, the reflux may be produced solely by partial condensation of the vapors, within 25 the column. For example, a suitable cooling fluid may be circulated through a coil 23, the turns of which are contained within the body of adsorptive material 14 so that the vapors undergo condensation and liquid condensate and reflux are 30 formed within the body of material itself. As will be understood, sufficient condensate is produced to maintain a substantial quantity of liquid hydrocarbons in intimate contact with the vapors and in agitated washing flow within the adsorptive material. The oil drawn from the base of column 13 through line 16, and including hydrocarbons heavier than gasoline, and perhaps also heavier fractions within the gasoline range, depending upon the charging stock and particular 35 temperature and pressure conditions, is taken through line 24 to a cracking still 25.

In still 25 the oil is subjected to cracking at temperatures and pressures that may be within the ranges stated with reference to cracking still 11, although generally it is preferred to crack the oil in still 25 at somewhat higher temperature and pressure, say within 50 to 100° F. higher temperature and up to 100 lbs. per sq. in. higher pressure, in view of the higher boiling range of the charging stock in still 25 where a lower boiling charging stock is being cracked in still 11. The cracked hydrocarbon stream is discharged through line 26 into a separating chamber or reaction zone 27, from the base of which carbon and unvaporized residue are withdrawn from the system through line 28. The cracked vapors flowing from chamber 27 through line 29 may be discharged through line 30 to be combined with the cracked hydrocarbon stream from the still 11 and thereby recirculated through chamber 13, or a part of all of the vapors may be taken from line 29 through line 31 and discharged at 32 into a second polymerizing chamber 33 charged with siliceous or catalytic material 34 of the same character as that contained in chamber 13. The polymerized vapors leaving chamber 13 through line 15 may also be passed into chamber 33 through line 34a, or all or a portion of the vapors may be discharged through line 35 directly to the dephlegmator or fractionating column 21.

The vapors introduced through line 32 to column 33 may be permitted to flow throughout adsorptive material 34 therein without introducing reflux thereto or without producing abnormal

condensation of the vapors, or a suitable reflux may be introduced through line 36 or the vapors partially condensed by coil 37, all as previously described in connection with the operation of clay column 13. As an alternative method of maintaining mixed liquid and vapor contact within chamber 33, valve 37a in the outlet line 38 may be operated by a liquid level control, diagrammatically indicated at 39, which maintains within the bottom of the chamber a minimum oil level L, below which the vapors are introduced from line 32 into a body of the oil. In this manner the oil is being continuously displaced upwardly within the clay body by the vapor flow, producing thorough commingling of the oil and vapor and their intimate contact with the clay.

Condensate removed from chamber 33 through line 38, and carrying polymerized and sulfur containing hydrocarbons as in the case of the oil stream in line 16, may be recirculated through line 39 to the cracking still 25, or discharged to storage through line 40. Vapors leaving chamber 33 through line 41 flow through line 35 to fractionating column 21, from the base of which heavier than gasoline fractions are withdrawn through line 42, and returned through line 42a to still 25, or taken to storage through line 42b. Leaving column 21, the vapors pass through line 43 to a final condenser 44 from which the condensate goes to receiver 45 and fixed and uncondensable vapors to the valved discharge line 46. As will be understood, fractionating column 21 and condenser 44 are merely illustrative of any suitable system for fractionating or further treating the vapors beyond the second clay column 33 to produce gasoline as a final product. The various vapor lines in the system are shown to contain valves which may be set to maintain proper operating pressures within the system, including the back pressures on the cracking stills, polymerizing chambers, fractionating column and final condenser. While generally it is preferred to control the pressure on the system by a valve or valves beyond the fractionating column, it will be apparent that the valves in the vapor lines may be regulated to maintain any desired differential pressures on the hydrocarbons within the cracking stills, polymerizing chambers and fractionating column.

While the invention contemplates using preferably and more generally a charging stock for cracking still 11 consisting of a relatively low boiling oil, as previously described, it is possible to adapt the system to operation on heavier 55 charging stocks by providing for the removal from the cracked hydrocarbon stream of carbon and heavy bodies that might otherwise produce excessive contamination of the adsorptive material in column 13. Where such heavier charging stock is employed, the cracked vapors leaving still 11 may be discharged through line 48 into a separating or reaction chamber 49 from which the vapors flow through line 50 to the clay column 13, and the unvaporized residuum is removed from the system through line 51.

From the foregoing description of the system, it will be seen that after initial cracking of the charging stock and initial polymerization of the vapors in chamber 13, relatively heavy fractions of the cracked hydrocarbons, as well as the polymerized bodies, are subjected to re-cracking and again subjected to polymerization in one or both of the clay columns, all in a manner such that an abnormally high percentage of potential aromatic or other high octane value hydro-

carbons is formed and converted within the system to gasoline fractions. As a result, I obtain a final gasoline distillate that is abnormally high in aromatic and non-detonating compounds, and which possesses an exceptionally high octane rating.

I claim:

1. The method of refining petroleum hydrocarbons that includes subjecting the hydrocarbons to cracking in a cracking zone, introducing cracked hydrocarbon vapors from said zone into a polymerizing zone containing a body of adsorptive material being constantly washed by condensed fractions of the vapors, passing the vapors through and in intimate contact with said material and condensate, removing polymer-containing unvaporized oil and condensate from said polymerizing zone, subjecting the removed oil and condensate to cracking in a second cracking and essentially non-hydrogenating zone separately from and independently of the vapors passing from the first mentioned cracking zone, subjecting cracked vapors from said second cracking zone to polymerization by contacting them with adsorptive material together with the first mentioned vapors, and treating the polymerized vapors from the hydrocarbons cracked in said cracking zones to produce gasoline.

2. The method of refining petroleum hydrocarbons that includes subjecting the hydrocarbons to cracking in a cracking zone, introducing cracked hydrocarbon vapors from said zone into a polymerizing zone containing a body of adsorptive material being constantly washed by condensed fractions of the vapors, passing the vapors through and in intimate contact with said material and condensate, removing polymer-containing unvaporized oil and condensate from said polymerizing zone, subjecting the removed oil and condensate to cracking in a second cracking and essentially non-hydrogenating zone separately from and independently of the vapors passing from the first mentioned cracking zone, subjecting cracked vapors from said second cracking zone to polymerization by contacting them with adsorptive material together with the first mentioned vapors in said polymerizing zone, and treating the polymerized vapors from the hydrocarbons cracked in said cracking zones to produce gasoline.

3. The method of refining petroleum hydrocarbons that includes subjecting the hydrocarbons to cracking in a cracking zone, introducing cracked hydrocarbon vapors from said zone into a polymerizing zone containing a body of adsorptive material being constantly washed by condensed fractions of the vapors, passing the vapors through and in intimate contact with said material and condensate, removing polymer-containing unvaporized oil and condensate from said polymerizing zone, subjecting the removed oil and condensate to cracking and vaporization in a second cracking and essentially non-hydrogenating zone separately from and independently of the vapors passing from the first mentioned cracking zone, separating unvaporized residuum from the resulting vapors and subjecting the last mentioned vapors to polymerization by contacting them with adsorptive material together with the first mentioned vapors, and treating the polymerized vapors from the hydrocarbons cracked in said cracking zones to produce gasoline.

4. The method of refining petroleum hydrocarbons that includes subjecting the hydrocar-

bons to cracking in a cracking zone, introducing cracked hydrocarbon vapors from said zone into a polymerizing zone containing a body of adsorptive material being constantly washed by condensed fractions of the vapors, passing the vapors through and in intimate contact with said material and condensate, removing polymer-containing unvaporized oil and condensate from said polymerizing zone, subjecting the removed oil and condensate to cracking and vaporization in a second cracking and essentially non-hydrogenating zone separately from and independently of the vapors passing from the first mentioned cracking zone, separating unvaporized residuum from the resulting vapors and subjecting the last mentioned vapors to polymerization by contacting them with adsorptive material together with the first mentioned vapors in said polymerizing zone, and treating the polymerized vapors from the hydrocarbons cracked in said cracking zones to produce gasoline.

5. The method of refining petroleum hydrocarbons that includes subjecting the hydrocarbons to cracking in a cracking zone, introducing cracked hydrocarbon vapors from said zone into a polymerizing zone containing a body of adsorptive material being constantly washed by condensed fractions of the vapors, passing the vapors through and in intimate contact with said material and condensate, removing polymer-containing unvaporized oil and condensate from said polymerizing zone, subjecting the removed oil and condensate to cracking and vaporization in a second cracking and essentially non-hydrogenating zone separately from and independently of the vapors leaving the first mentioned cracking zone, separating unvaporized residuum from the resulting vapors and subjecting the last mentioned vapors to polymerization by contacting them with adsorptive material together with the first mentioned vapors, and treating the polymerized vapors from the hydrocarbons cracked in said cracking zones to produce gasoline.

6. The method of refining petroleum hydrocarbons that includes subjecting the hydrocarbons to cracking in a cracking zone, passing cracked hydrocarbon vapors from said zone successively through two polymerizing zones each containing

50 a large, vertically extending body of adsorptive material, maintaining the vapors in intimate contact with said material in the presence of condensed fractions of the vapors, removing polymer-containing condensate from the polymerizing zone first entered by the vapors, subjecting the removed condensate to cracking in a second cracking and essentially non-hydrogenating zone separately from and independently of the vapors passing from the first mentioned cracking zone, separating unvaporized residuum from the resulting vapors and subjecting the last mentioned vapors to polymerization together with the first mentioned vapors in at least one of said polymerizing zones, and treating the polymerized vapors from the hydrocarbons cracked in said cracking zones to produce gasoline.

7. The method of refining petroleum hydrocarbons that includes subjecting the hydrocarbons to cracking in a cracking zone, passing cracked hydrocarbon vapors from said zone successively through two polymerizing zones each containing a large, vertically extending body of adsorptive material, maintaining the vapors in intimate contact with said material in the pres-

ence of condensed fractions of the vapors, removing polymer-containing condensate from both said polymerizing zones, subjecting the removed condensate to cracking in a second cracking and essentially non-hydrogenating zone separately from and independently of the vapors passing from the first mentioned cracking zone, separating unvaporized residuum from the re-

5 sulting vapors and subjecting the last mentioned vapors to polymerization together with the first mentioned vapors in at least one of said polymerizing zones, and treating the polymerized vapors from the hydrocarbons cracked in said cracking zones to produce gasoline.
